UNITED STATES PATENT OFFICE.

CHARLES D. LANNING, OF DORCHESTER, MASSACHUSETTS.

WARP STOP-MOTION FOR LOOMS.

No. 861,191.

Specification of Letters Patent.

Patented July 23, 1907.

Application filed June 7, 1907. Serial No. 377,732.

To all whom it may concern:

Be it known that I, CHARLES D. LANNING, a citizen of the United States, residing at Dorchester, in the county of Suffolk, State of Massachusetts, have invented an Improvement in Warp Stop-Motions for Looms, of which the following description, in connection with the accompanying drawings, is a specification, like letters on the drawings representing like parts.

10 My invention relates to warp stop motions for looms, being more particularly concerned with, but not limited to, the provision of improvements to be used in connection with electrical warp stop motions.

The invention will be best understood by reference 15 to the following description when taken in connection with the accompanying illustration of one specific embodiment thereof, the scope of the invention being more particularly pointed out in the appended claims.

In the drawing, wherein a single type of the invention is illustrated, Figure 1 is a side elevation of a loom frame with attachments applied thereto embodying one form of my invention; Fig. 2 is a detail view, partly in side elevation and partly in vertical section, of one manner of supporting the lease rods in accordance with my invention; Fig. 3 is a top plan view of a portion of the mechanism illustrated in Fig. 2.

In the drawing, I have shown my invention as applied to a particular construction of loom and a particular type of warp stop motion, but it is to be understood 30 that such is for the purpose of illustration only, and that my invention in any desired embodiment thereof may be adapted to looms and stop motions of other and quite different types, whether electrical or mechanical.

Referring to the drawings, I have illustrated the side 35 member 1 of a loom provided with a well-known construction of belt shifting device, which is thrown into operation through the action of the drop bars of the warp stop motion in a manner well understood in the art, it being unnecessary to describe in detail the construction and operation of such belt shifting device.

In the present instance, I have shown the loom as provided with circuit establishing devices for the warp stop motion of the same general construction as is described in Patent No. 690,636 to Coldwell & Gildard. 45 To the side frame members 1 are adjustably bolted the upright angle brackets 2, which sustain the various contact devices for the warp stop motion. These may comprise a single tubular contact bar 3 (see Fig. 2) supported at its ends by suitable insulating plugs, 50 which may be secured in any suitable manner upon the angle brackets 2. Connection is had between the tubular contact bar 3 and one side of the circuit leading to the controlling magnet 4 by means of a contact wire 5 (see Fig. 1), preferably passing through one of the insulating plugs. The other side of the circuit, as 55 will be understood by those skilled in the art, is con-

nected through the frame of the machine to the overhead circuit and guiding rods 6 (see Fig. 2), which are shown as converging toward their upper edges and secured at their opposite ends to lugs projecting inwardly from the brackets 2.

In the present type of my invention, supported above the contact rods 6 upon the brackets 2 and engaging at their ends with inturned studs sustained by said brackets are tubular lease members, herein represented as rods 7 and 8, which maintain the threads of the warp in a leased condition with successive threads crossed in a fashion well understood to those skilled in the art.

Upon successive warp threads are suspended drop 70 bars 9, herein and preferably arranged in two sets, the drop bars of one set being sustained by one series of threads and having their open depending legs embracing one of the circuit rods and the drop bars of the other set being sustained by the other series of threads 75 and embracing the other circuit rod. In the illustrated construction, as in the aforesaid prior patent, No. 690,636, the drop bars are provided with closed longitudinal slots 10, through each of which passes a transverse retaining rod, the rod for one set of bars being indicated at 11 and that for the other set being indicated at 12. The ends of said retaining rods are suitably supported in any desired manner in the brackets 2. It is, of course, to be understood that any desired form or type of drop or indicating bars may be 85 employed.

The drop bars and detectors are maintained in accurate contact with the contact rods 6 under all conditions of use. A break in one of the warp threads causes the drop bar supported thereby to fall and contact with 90 the contact bar 3, completing the circuit and energizing the electro-magnet controlling the device for the immediate stoppage of the loom.

It is quite desirable that the leasing members 7 and 8 should so control the position of the threads that the 95 desirable relation between the drop bars and the co-operating contact device should be maintained without displacement, as otherwise vibratory movements of the lay may cause disarrangement of the drop bars relatively to the contact rods. It has been found, 100 however, that if the lease rods be held rigidly and fixedly that increasing frictional resistance is apt to be put upon the warp threads particularly if the attendant is careless in adjusting the warp or the harness. To avoid the enumerated and other objections, I preferably mount each lease rod for movement in conformity with the leveling or compensating movements of the warp. In the type of stop motion herein selected, the leasing members 7 and 8 serve not only the usual function common in looms of separating the warp 110 threads in such manner that the warp feeds easily and the threads are properly separated and control thereof

for repair and manipulation is rendered easier, but in addition the leasing members serve the additional function of supporting the warp against the weight of the drop bars. Moreover, where the special form of drop bar here shown is used, the advantages incident thereto are obtained. By providing a construction and arrangement whereby the guiding means for the drop bars and the devices intended to coöperate with the drop bars in their indicating movement to stop the loom, are held in fixed relation so as not to partake of the movements of one or more of the leasing members and preferably are rigidly connected to the loom frame, while the warp supporting lease members or rods, which not only separate the warp but support the same against the weight of the drop bars as above noted, are given a certain freedom of movement which preferably is so confined as not materially to move the drop bars lengthwise of the warps, not only is more freedom given to the warp in its travel by the lease rods and through the drop bars, but greater certainty of stopping action of the stopping mechanism is obtained. A limited movement of the lease rods or members is moreover advantageous, because of the fact that in placing a warp in the loom the weaver or loom fixer may not so adjust the harnesses that the middle point of the shed may be in the same plane as the top of the wheel roll and the lease rods. This supporting of the lease rods so as to permit slight movement thereof compensates for this, as well as permitting slight movement when there is a variation of tension or other change in the warp. A warp thread having broken, the drop bar positioned thereon falls and is guided by a stationary guide bar into contact or engagement with the lower coöperating device entirely free of any further movement that may be imparted to the warp supporting lease rods. Not only so, but the movement of the lease rods and the supported threads and drop bars tend, if anything, to increase the tendency of the released drop bar on the broken thread to fall. All the advantages therefore of permanently positioned guiding and stopping devices are had together with the advantage of relatively freely moving warp supporting bars and lease rods or members.

In the present type of the invention, in each bracket 45 or casting 2, I preferably provide straight or right line and herein vertically disposed sockets 13 having dovetailed lateral edges 14 as represented in Fig. 3 and mount in each of said sockets a block 15 guided in said dovetailed portions of said sockets. Preferably 50 said blocks are provided with lugs to receive and support the leasing members or rods 7 and 8.

Preferably I provide means whereby not only are the lease rods or members cushioned but the weight of the leasing members and coöperating parts is taken 55 off the warp, the warp being supported by the leasing members, and hence by the support of the latter. In this embodiment of the invention, I accomplish this result by providing resilient members or springs in operative relation to the lease rods under compression 60 or tension to support the rods. Preferably each block 15 is provided with upper and lower projecting lugs 16 and 17 to receive the ends of coil springs 18 and 19, whereby the vertical movements of said leasing rods in conformity with the leveling requirements of the 65 warp, are cushioned. Herein the coil springs 19 are

represented as mounted in recessed sockets of less diameter than those receiving the blocks 15, lugs 20, if desired, extending upwardly from the bottom of the sockets 2 to receive the coil springs, which act to support the weight of the lease rods and coöperating 70 parts. Any suitable means may be provided to limit the vertical and independent movement of said lease members or rods. Herein the downward movement of said rods is limited by the provision of shoulders 21 afforded by the reduced diameter of the sockets where- 75 in the springs 19 are positioned. The coil springs 18 may be received within the movable plugs 22 having sockets therein to receive said springs and provided with downwardly projecting lugs 23. The lower edge of each plug 22 affords a fixed stop for the upward 80 movement of the lease members or rods, said plugs, if desired, being capable of vertical adjustment, so that a variable path of movement of the leasing members may be provided. Preferably a plate 24 is attached in any suitable manner to the inner face of each 85 bracket 2, it being provided with suitable vertically elongated slots 25, one of which is shown in Fig. 2 to permit the vertical warp caused movement of the lease rods in accordance with the compensating or adjusting movements of the warp. 90

It is apparent that any suitable means may be provided to support the lease rods, whereby their vertical warp caused movement independently of each other may be permitted.

It will be observed that a confined independent 95 movement of the warp supporting lease rods is provided, such movement, in the present type of the invention, being a vertical sliding movement, that not only is confined within certain limits but is cushioned.

It is apparent that instead of providing for a truly 100 vertical movement, the lease rods may be mounted for movement in an inclined path preferably in the direction of movement of the warp threads.

I do not herein claim broadly warp supporting lease rods mounted for movement in conformity with the 105 leveling requirements of the warp, and mounted for such movement independently of means coöperating with loom stopping mechanism, whether electrical or mechanical, but I do claim certain means whereby a plurality of such lease rods are mounted for movement 110 independently of each other. By mounting such rods for movement in conformity with the leveling requirements of the warp, independently of each other, then, if the central position of the harnesses be either above or below the top of the whip roll or other warp 115 support, each lease rod is free to position itself in accordance with such line of inclination of the warp; unrestrained by the other rod or rods, the movement of which may be less or more than that of the first mentioned rod, dependent upon their relative positions with respect to the whip roll. In other words, by mounting the lease rods for movement independently of each other, a differential movement may be imparted to the several lease rods, the extent of which depends upon their respective positions with respect 120 to the harnesses or the whip roll. I do not herein claim means for supporting the lease rods to take their weight off the warp, save in combination with independently mounted lease rods.

Having thus described one type or embodiment of 130

my invention, I desire it to be understood that although specific terms are employed, they are used in a generic and descriptive sense and not for purposes of limitation, the scope of the invention being set forth 5 in the following claims.

1. In a warp stop motion for a loom, the combination with a plurality of warp thread supporting lease rods dividing the warp into sheets and mounted for up and down right line movement independently of each other, a plurality of series of drop bars supported by the warp threads where so separated into sheets, guiding means to guide the loom stopping movement of the drop bars, and means co-operating with the loom stopping mechanism and with which an indicating drop bar is adapted to co-operate, said 10 guiding means and said means co-operating with the loom stopping mechanism being supported to permit compensating movement of the lease rods independently thereof.
2. In a warp stop motion for a loom, the combination with a plurality of warp thread supporting lease rods dividing the warp into sheets and mounted for cushioned up and down right line movement independently of each other in accordance with the compensating movements of the warp, a plurality of series of drop bars, said series of bars being respectively supported upon the respective sheets of the warp between said lease rods, guiding means to guide the loom stopping movement of the drop bars, and means co-operating with the loom stopping mechanism and with which an indicating drop bar is adapted to co-operate, said lease rods being supported independently of said guiding 5 means and said co-operating means so as to permit the warp caused movement thereof independently of any movement of said guiding means and said co-operating means.
3. In a warp stop motion for a loom, the combination with a plurality of warp thread supporting lease rods mounted for up and down right line warp caused movement independently of each other, of one or more series of drop bars supported on the sheets of the threads formed by said lease rods, guiding means to guide the movement of an indicating drop bar, and means co-operating with said indicating drop bar to stop the loom, said guiding means and said co-operating means being supported independently of said series of lease rods.
4. In a warp stop motion for a loom, the combination with a plurality of lease rods mounted for up and down right line movement independently of each other in conformity with the leveling requirements of the warp and within defined limits, said lease rods dividing the warp into sheets, a plurality of series of drop bars respectively supported upon the respective related series of sheets and between said lease rods, guiding means to guide the movement of an indicating drop bar, and means to co-operate with said indicating drop bar to stop the loom, said guiding means and said co-operating means being supported to permit the described movement of one or more of said lease rods independently of said guiding means and said co-operating means.
5. In a warp stop motion for a loom, the combination with a plurality of warp thread supporting lease rods dividing the warp into sheets and mounted for up and down right line movement independently of each other, guiding means for such vertical movement of said lease rods, a plurality of series of drop bars supported by the warp threads where so separated into sheets, guiding means to guide the loom stopping movement of the drop bars, and means co-operating with the loom stopping mechanism and with which an indicating drop bar is adapted to co-operate, said guiding means and said means co-operating with the loom stopping mechanism being supported to permit compensating movement of the lease rods independently thereof.
6. In a warp stop motion for a loom, the combination with a plurality of warp thread supporting lease rods dividing the warp into sheets and mounted for up and down right line movement independently of each other, 75 guiding means for such vertical movement, cushioning means for such movement, a plurality of series of drop bars supported by the warp threads where so separated into sheets, guiding means to guide the loom stopping movement of the drop bars, and means co-operating with the loom stopping mechanism and with which an indicating drop bar is adapted to co-operate, said guiding means and said means co-operating with the loom stopping mechanism being supported to permit movement of the lease rods independently thereof, in conformity with the requirements of the warp.
7. In a warp stop motion for a loom, the combination with a plurality of warp thread supporting lease rods dividing the warp into sheets and mounted for up and down right line differential movement with respect to each other, 80 means to limit such movement, a plurality of series of drop bars supported by the warp threads where so separated into sheets, guiding means to guide the loom stopping movement of the drop bars, and means co-operating with the loom stopping mechanism and with which an indicating drop bar is adapted to co-operate, said guiding means and said means co-operating with the loom stopping mechanism being supported to permit compensating movement of the lease rods independently thereof.
8. In a warp stop motion for a loom, the combination with a plurality of warp thread supporting lease rods dividing the warp into sheets and mounted for up and down right line movement independently of each other, a plurality of series of drop bars supported by the warp threads where so separated into sheets, guiding means for the stopping movement of the drop bars, and means co-operating with the loom stopping mechanism and with which an indicating drop bar co-operates, said guiding means and said means co-operating with the loom stopping mechanism being supported to permit warp caused movement of the 100 lease rods independently thereof.
9. In a warp stop motion for a loom, the combination with a plurality of warp thread supporting lease rods dividing the warp into sheets and mounted for up and down right line movement independently of each other, a plurality of series of drop bars supported by the warp threads where so separated into sheets, means to take the weight of the said lease rods off the warp, guiding means for the stopping movement of the drop bars, and means co-operating with the loom stopping mechanism and with which an indicating drop bar co-operates, said guiding means and said means co-operating with the loom stopping mechanism being supported to permit warp caused movement of the 105 lease rods independently thereof.
10. In a warp stop motion for a loom, the combination with a plurality of warp thread supporting lease rods dividing the warp into sheets and mounted for up and down right line movement independently of each other, a plurality of series of drop bars supported by the warp threads where so separated into sheets, resilient means to support the lease rods, guiding means for the stopping movement of the drop bars and means co-operating with the loom stopping mechanism and with which an indicating drop bar co-operates, said guiding means and said means co-operating with the loom stopping mechanism being supported to permit warp caused movement of the lease rods independently thereof.
11. In testimony whereof, I have signed my name to this specification, in the presence of two subscribing witnesses.

CHARLES D. LANNING.
